(57) **CLAIM**

The ornamental design for a hanging toilet bowl brush and caddy, as shown and described.

DESCRIPTION

FIG. 1 is a front isometric view of a hanging toilet bowl brush and caddy showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an exploded isometric view of the components of hanging toilet bowl brush and caddy.

The broken lines show portions of the design that form no part of the claimed design.

1 Claim, 5 Drawing Sheets
